UNITED STATES PATENT OFFICE.

GEORGE R. E. MILLIGAN, OF LOS ANGELES, CALIFORNIA.

PAD FOR HERNIA TRUSSES.

Application filed June 24, 1926. Serial No. 118,177.

An object of this invention is to provide a superior truss pad which will be easy to the wearer, and will firmly and gently hold the hernia, and that is adjustable to different cases, and to different conditions in any specific case.

The invention contemplates the provision of a truss pad having a main body cushion and a button adjustable to said main body cushion, and means for adjusting the button to cause the compression of the cushion.

The invention also includes specific constructions, parts and a novel combination and arrangement of parts, adapted to perfect application of the main principle of the invention.

Another feature of the invention is adaptability to the treatment of hernia in cases of corpulent persons.

20 An advantage of the invention is that any desired pressure adjustment may be made and the pad may be adapted to different applications of pressure upon the hernia and such pressure may be limited by support of 25 the abdominal walls adjacent to the rupture.

Other objects, advantages and features of invention may appear from the accompanying drawing, the subjoined detailed description and the appended claims.

30 The accompanying drawing illustrates the invention.

Figure 1 is a view of one form of the pad construction with the button retracted and the base compressed.

35 Fig. 2 is an elevational view of the contacting side of the pad with the button retracted and base compressed and wherein parts are broken away to expose interior construction at different depths.

40 Fig. 3 is transverse section on line x^3-x^3 of Fig. 2, illustrating one form of the pad with the button in extended position.

Fig. 4 is a similar section of a pad with the button retracted to rest on a resilient cushion, broken lines indicating a released position of the button.

45 Dot and dash lines indicate the position where the cushion has been further compressed by pressure of the button upon the 50 person, not shown, of the wearer of the truss.

Fig. 5 is an elevation of the back of a pad conforming in a general way to the construction shown in the other views.

55 Parts are broken away to expose parts otherwise hidden.

Fig. 6 is an axial section of another form of the invention.

The pad comprises two elements one or both of which may contact with the parts 60 affected according to the relative adjustment of such elements; and for convenience of description I term one of the elements, the base, and the other a button.

The base is shown as built up of a leather 65 disk 1, a sponge rubber cushion-body 2 cemented to the disk 1 and having a central bore 3, and a covering 4 made of a circular piece of buckskin or other soft pliable material, cemented centrally to the top of the 70 cushion, and drawn over the cushion and around the edges of the leather disk 1, and drawn tight and held by a draw string 5 run through the covering material near the edge thereof, and puckering the circular edge 75 of the cover onto the back of the leather disk at 6, the ends of the pucker string being tied together so as to hold the cover tightly in place. Then the portion of the cover that is over the bore 3 is slit radially to make 80 points 7, and then such points are bent down and cemented to the inside of the bore. The base is then finished by applying a metal 85 backing plate 8 onto the puckered edge of the cover and securing it to the leather disk 1, by means of screws 9 that clamp the plate onto the puckered edge and the draw string.

The disk 1 and backing plate 8 are provided with a smooth walled hole 10 through 90 which a screw 11 is inserted for the purpose of adjustably holding the button 12 in desired relation to the base or ring 2.

The button 12 is provided at its back with a stem 13 that is provided at its back 95 end with a plate 14 having a threaded hole 15, which the threaded portion 16 of the screw 11 engages.

Said screw is provided with a head 17 and has a smooth shank 18, between the threaded portion 19 and the head 17, to move freely through the hole so that when it is desired, the screw can be turned to draw the button toward the base; and in the case of the resilient cushion like base, the button may 105 compress the cushion.

Said button is shown in Figs. 1-4, as a cushion 20 of resilient sponge rubber cemented onto a metal plate 21 that is fixed by screws 22 to the stem 13; and the sponge 110 and plate are covered by a cover 23, cemented to the top of the cushion 20 and

drawn around said cushion 20 and fastened by a pucker string 24 that draws the cover tightly onto the cushion and leather plate.

In the form shown in Fig. 4, pressure 5 upon the button may compress the cushion 2, in which case the screw protrudes through the plate 1, as shown in dot and dash lines; and when the pressure on the button is relieved the resilient cushion returns the button and the screw head to the set position shown in solid lines in Fig. 4.

In Fig. 3 a set nut 25 is shown screwed onto the screw to clamp the leather disk 1 against the head 17 so that the stem 13 15 of the button is held in fixed adjustment with respect to the cushion.

The metal plate 8 is shown provided with holes 26 to receive screws for the purpose of fastening the pad to the pad supporting 20 element of a truss, not shown.

Preferably the periphery of the cushion 2 is flush with the periphery of the leather disk 1, but in the resilient button it is preferable to provide a cushion 27 of greater 25 diameter than the leather plate 1 and in making the button, the cover 23 is cemented across the top of the cushion and is then brought snugly around and under the cushion and is secured by a draw string 24 30 and tied against the stem 13.

In practical use the surgeon or other skilled person may adjust the button with relation to the plate 8, by turning the screw 11 in Fig. 4, or may turn the button to screw it 35 onto the screw; and when the proper adjustment is secured, and the truss, not shown, with its pad or pads is fitted to the wearer, further attention is unnecessary and the wearer may take off and put on the truss at 40 pleasure with the assurance that the re-

duction of the hernia will be the same in each instance.

In the form shown in Fig. 6, the base cushion 29 is provided with a chamber 30 into which the button 31 may be drawn by 45 the screw 11 so that the ring 33 formed by the perimeter of the base cushion may serve more fully to support the region immediately around the rupture.

I claim:

1. A pad for hernia trusses comprising a base member formed of resilient material; a button connected to said base member and adapted to be adjusted to compress said base member.

2. A pad for hernia trusses comprising a compressible base member; a button connected to said base member and means for adjusting the button to compress said base member.

3. A hernia pad comprising a base plate; a cushion member on said base plate provided with a bore; a plunger in the bore; a button carried by said plunger and a screw connected to the base plate and adapted 65 to move the plunger toward said base plate to cause the button to compress said cushion member.

4. A hernia pad comprising a base plate; a cushion on the base plate provided with a bore; a plunger in the bore; a screw extending through the base plate and adapted to move the plunger toward and from the base plate, and a button on the end of the plunger adapted to be retracted by said screw to compress said cushion.

In testimony whereof, I have hereunto set my hand at Los Angeles, California, this 17th day of June, 1926.

GEORGE R. E. MILLIGAN.
